MAX MELZER, OF BUCHHOLZ, GERMANY, ASSIGNOR TO SIGMUND BASCH, OF NEW YORK, N. Y.

BUTTON.

1,088,835.

Specification of Letters Patent.

Patented Mar. 3, 1914.

Application filed July 28, 1911. Serial No. 641,058.

To all whom it may concern:

Be it known that I, MAX MELZER, a subject of the German Emperor, and a resident of Buchholz, Saxony, Germany, have made 5 a new and useful Invention in Buttons, of which the following is a specification.

This invention relates to the manufacture of a new form of button closely resembling in appearance a crocheted button of the peculiar construction and manufacture hereinafter more fully set forth.

In the drawings all views being on a greatly enlarged scale, Figure 1 illustrates the side view of one form of the buttons and 15 Fig. 2 a top view thereof. Figs. 3 and 4 illustrate the cotton foundation for the button and Fig. 5 is an enlarged view showing the threads used and their relation to each other in the finished covering for the foundation. Fig. 6 is a section on lines 6—6 of Fig. 2.

Ordinary buttons of the general character to which those of this application relate have been made by hand, the foundation 25 consisted of a perforated wooden disk or ball and the covering for the foundations of this nature were crocheted upon them by hand work. In some cases, the foundation was made of cotton, but in those cases they 30 were simply lumps of cotton, having no central opening like the wooden disks or balls. The crocheted wooden buttons could not be readily washed, although the fact that hand labor was employed in making them, made a 35 preliminary washing thereof essential. The cotton crocheted buttons, when washed, remained soggy and never had that appearance of freshness which a new manufactured article should have. Many attempts were 40 made to produce crocheted buttons by machinery but the looms which can produce crocheted work are incapable of applying such work to an irregularly shaped body, whether of cotton, wood, or other material.

45 I, therefore, abandoned the idea of making crocheted buttons by machinery as an impossibility and studied to produce a button which, although not crocheted, would have all the advantages of a machine manufactured product and at the same time create the effect of a crocheted button. After many experiments, I discovered that I could produce a crocheted effect by selecting certain peculiar types of thread and weaving 50 them together in the ordinary manner, and

that I could in this way produce a button closely resembling a crocheted button and having all the advantages of the hand crocheted buttons and in addition thereto, certain additional advantages of great importance in this art. The fundamental consideration upon which my invention is based is that I use a substantially invisible series of threads as the foundation or warp threads and a twisted visible thread as the 60 weft thread. The fabric thus woven upon a suitable foundation so that the lines of the twisted threads will be diagonal as shown in Fig. 1, will produce the effect of a hand crocheted button, and being produced by 65 well known machinery, can be applied to the foundation with great ease.

In the preferred form of my invention, I employ a foundation such as is shown in Figs. 3 and 4, which consists of a compressed cotton disk having a central aperture. Naturally the disk may assume other forms which are equally suitable to the formation of these new buttons. For some purposes, the compressed cotton contains a mixture of some suitable material which, when the cotton is moistened, will cause the button to become hard upon drying. Portland cement or plaster of Paris are examples of such suitable materials. A great many of 80 such substances are known and for that reason no particular substance is selected as preferable. When such a hydraulic cement is used, the button has the advantage of being capable of attachment to a garment by 85 means of a sewing machine, the entire structure being soft and affording no obstruction to the needle. After the garment has been washed, the buttons are all hard, in which condition they remain thereafter. 95

In the drawings, the foundation is designated as *c*. This foundation may be made of compressed cotton or it may be otherwise shaped to the proper form by rolling up a portion of the cotton spirally and then pressing it, or otherwise molding it in place. Many other methods of forming this foundation may be employed. 100

As will be seen from Fig. 5, the weaving of the threads *a* and *b* is conducted in such manner that the relatively thin parallel invisible weft threads *a* will form a continuous diagonal line, whereas in the preferred form, the relatively thick glossy, twisted threads *b* are so woven that each appar- 110

ently continuous diagonal line thereof is composed of a number of threads; thus, the thread *d* has a visible portion *e* in the diagonal line *f* and its next visible portion 5 will be *g* in the diagonal line *h*; this peculiar effect is brought about by the employment of a fine thread which follows the apparent line of diagonalism produced by the thick threads. This fine thread *i* running 10 as it does over the warp thread *a* but alternately under successive threads *b*, becomes entirely covered by the threads *b* so that no portion of it is visible. Nevertheless, it serves to hold the thick threads in their 15 proper position upon the button so as to produce the effect of apparently diagonal thick lines, which look as if they were formed of a continuous thread, but which, in fact, are formed of visible units each 20 from a different thread. These threads are closely woven upon the foundation so that they will sink into the surface of the foundation which thus acts as a fairly rigid support for the covering. If the covering is 25 removed from these buttons, the foundation, even though it be composed of compressed cotton, will be found to show the indentations where the covering threads have rested upon them. Having formed the foundation, I apply to it the covering shown in 30 Fig. 5. In that figure the threads *a* are what I call the invisible threads and in the preferred form, I use a series of three or four of such threads parallel to each other 35 for each warp thread, as clearly shown in Fig. 5. The twisted or weft thread *b* passes alternately under and over the weft threads and being relatively thick and shiny, such threads are the threads which produce the 40 optical effect. The combination of this method of weaving and of the size and gloss of the threads and their twisted condition are, to my mind, responsible for the effect produced by the button as a whole. The 45 ends of the woven fabric are retained in place within the opening in the foundation *c*, as shown in Fig. 6.

The finished button being entirely made by machinery is a clean and attractive structure capable of being fed to the work in 50 connection with which they are to be used by machinery and capable of being fastened thereto by a sewing machine, in which respect they differ essentially from the wooden foundation crochet buttons of the prior art. The needle of the sewing machine is intended 55 to pass through that portion of the fabric which is contained within the hollow opening of the foundation, but even if the 60 needle passes through the foundation itself, the effect will not be marred. Needless to say the cost of production of such buttons as compared with hand crocheted buttons is exceedingly small. With these buttons 65 tons, I am enabled to supply the full de-

mand for crocheted buttons, which are a highly appreciated adornment for feminine apparel and which could not possibly be supplied in sufficient quantities by the limited amount of available hand labor.

70

Having thus described my invention, what I claim is:

1. As a new article of manufacture, a button, having the appearance of a crocheted button, comprising a foundation and a covering composed of interwoven thin and thick threads, both sets of threads starting outward from the central portion of the top of the button in a substantially radial direction and curving along the upper side of the button in opposite directions to form intersecting spirals, the spirals of the thick threads being longer than those of the thin threads.

75

2. As a new article of manufacture a button, having the appearance of a crocheted button, comprising a foundation of soft yielding material having a central opening and a covering composed of interwoven thin and thick threads both sets of threads being concentrated in said central opening, the threads passing out from said central opening in a substantially radial direction and extending over the upper side of the button in spiral curves, the thin threads curving in one direction and the thick threads in another, the spiral of the thick threads being longer than that of the thin threads, the thick and thin threads alternately overlapping to produce a weave such that the visible loops of adjacent thick threads extend in diagonal lines cutting the curves of both sets of threads and invisible threads extending under said loops along 100 said diagonal lines.

90

3. As a new article of manufacture a button, having the appearance of a crocheted button comprising a soft yielding foundation having a central opening and a covering composed of interwoven thin and thick threads starting radially from said central opening and curving spirally over the upper face of the button the thin threads curving in one direction and the thick threads in an opposite direction, the thin threads being 110 arranged in groups, each group alternately passing over and under the thick threads to form a weave resembling crocheting, the loops of the thick threads being arranged in diagonal rows and single fine threads 115 passing through said diagonal rows under said thick threads and over said groups of thin threads so as to remain invisible for holding said diagonal loops in position on said foundation.

120

4. As a new article of manufacture a button, having the appearance of a crocheted button comprising a soft yielding foundation having a central opening and a covering composed of interwoven thin and thick 130

125

threads starting radially from said central opening and curving spirally over the upper face of the button the thin threads curving in one direction and the thick threads in an opposite direction, the thin threads being arranged in groups, each group alternately passing over and under the thick threads to form a weave resembling crocheting, the loops of the thick threads being arranged in diagonal rows, single fine threads passing through said diagonal rows under said thick threads and over said groups of thin threads so as to remain invisible for hold-

ing said diagonal loops in position on said foundation and material impregnating said foundation adapted in the presence of water to harden the same and thus retain said threads in their proper relations. 15

In testimony whereof I have hereunto set my hand in the presence of two subscribing witnesses. 20

MAX MELZER.
